UNITED STATES PATENT OFFICE

95,443

DESIGN FOR A COMBINED LAWN SPRINKLER AND BIRD BATH

William E. McCormick, New York, N. Y.

Application June 29, 1933, Serial No. 48,596

Term of patent 3½ years

To all whom it may concern:

Be it known that I, William E. McCormick, a citizen of the United States, residing at the Borough of Bronx, county of Bronx, city and State of New York, have invented a new, original, and ornamental Design for a Combined Lawn Sprinkler and Bird Bath, of which the following is a specification, reference being had to the accompanying drawing, forming part thereof.

The figure is a perspective view of a combined lawn sprinkler and bird bath showing my new design.

I claim:

The ornamental design for a combined lawn sprinkler and bird bath, as shown.

Signed at the city of New York, in the county of New York, State of New York, this 15th day of May, 1933.

WILLIAM E. McCORMICK.
